UNITED STATES PATENT OFFICE.

HERMAN L. LOHEIDE, OF ST. LOUIS, MISSOURI, ASSIGNOR TO LOHEIDE MANUFACTURING COMPANY, OF ST. LOUIS, MISSOURI, A CORPORATION OF MISSOURI.

DESIGN FOR A HUMIDIFIER.

48,392.

Specification for Design.

Patented Jan. 4, 1916.

Application filed April 3, 1915. Serial No. 19,067. Term of patent 14 years.

To all whom it may concern:

Be it known that I, HERMAN L. LOHEIDE, a citizen of the United States, residing at the city of St. Louis, State of Missouri, have invented a new, original, and ornamental Design for a Humidifier, of which the following is a specification, reference being had therein to the accompanying drawing, forming part thereof.

The drawing is a perspective view of a humidifier showing my new design.

I claim:

The ornamental design for a humidifier substantially as shown.

In testimony whereof, I hereunto affix my signature in the presence of two witnesses.

HERMAN L. LOHEIDE.

Witnesses:

WALTER C. GUELS,
NANCY C. THOMAS.
